UNITED STATES PATENT OFFICE.

JOHN HARVEY AND FREDERICK HERKSTROETER, OF ST. LOUIS, MO.

IMPROVEMENT IN LAP-SHAVERS AND LEATHER-SPLITTERS.

Specification forming part of Letters Patent No. 47,300, dated April 18, 1865.

To all whom it may concern:

Be it known that we, JOHN HARVEY and FREDERICK HERKSTROETER, of the city and county of St. Louis, and State of Missouri, have invented a certain new Improvement in the Lap-Shaving and Leather-Splitting Machine of John Harvey and F. H. Harvey, the patent on which was allowed on the 9th day of May, 1864; and we do hereby declare that the following is a full, clear, and exact description thereof, reference being had to the accompanying drawings and the letters of reference marked thereon.

Figure 1 is a perspective view of one of the improved machines. Fig. 2 is a transverse section of a machine. Fig. 3 is an end elevation of a machine.

To enable those skilled in the art to make and use our invention, we will proceed to describe its construction and operation.

We use the frame A, the eccentric-roller B, and the knife C in substantially the same manner as they are used in the machine invented by John Harvey and F. H. Harvey, in which the frame A consists of a bed-plate with an upright post on either end of it. These upright posts sustain the eccentric roller B between them and the cutting-knife C directly over the roller B. The front edge of the knife C should be in a vertical line passing through the center of the journal x of the roller B. A continuation of the journal x, after passing through one of the supporting-posts, has a handle, b, attached to it for the purpose of turning the roller B.

The improvements which we now make on the above-described machine are the adjustable pillar-block a, the pressure-roller d, the gage e, and the adjustable lock-pin i, all of which are used for the purposes hereinafter described.

Into both of the upright posts of the frame A are fitted the adjustable pillar-blocks a. (Seen in Figs. 1 and 3.) These pillar-blocks form the bearings of the journal x, and are secured to the posts of the frame A by means of the screws n n, which pass through slots left in the pillar-blocks for that purpose. By turning up the screws n n the pillar-blocks will be secured in position. When the screws n n are slack, the pillar-blocks may be moved up

or down, as may be required to bring the highest part of the eccentric B when it is turned up in the same plane with the bottom side of the knife C.

The pressure-roller d is introduced between the two posts of the frame A, so that its lower edge, when down, will be in the same plane with the bottom side of the knife. The journals w of the roller d pass through vertical slots left in the upper ends of the posts of the frame A for that purpose, and are held down by means of spiral springs within the posts. The object of the roller d is to press the leather during the process of cutting down hard upon the roller B, so that it cannot run up too high on the knife and be cut off.

The gage e is a metal plate fastened to the machine by means of the two wires h h, which pass through lugs y on the posts, and may be held fast by means of set-screws. The gage e may be set at a greater or lesser distance from the edge of the knife, and it will thereby regulate the length of the lap, as the end of the strap or piece of leather to be shaved should be put through the machine until it stops against the plate of the gage e.

There is a series of holes bored in one of the ends of the eccentric roller B, as shown in Fig. 3. Into any of these holes the lock-pin i may be inserted, which will stop the motion of the roller when it strikes against the frame A.

When the machine is to be used as a lap-shaver, the end of the piece of leather to be shaved should be inserted between the roller B and the knife C until it stops against the gage e; then the roller B should be turned around by means of the handle b at the same time that the leather is withdrawn, and the result of the operation will be a smoothly-shaved lap of regular tapes.

When the machine is to be used as a leather-splitter, the gage e should be removed entirely from the machine, the eccentric turned round to any desirable point, and the lock-pin i inserted into any one of the holes made in the eccentric B for that purpose. The pin i should be put into the hole nearest the post of the frame when the eccentric is in proper position, and it will then come in contact with the post and hold the eccentric in the desired

position while the leather is pulled through and evenly split.

Having described our invention, what we claim as new, and desire to secure by Letters Patent, is—

The adjustable pillar-block *a*, the pressure-roller *d*, the gage *e*, and the adjustable lock-

pin *i*, arranged and operating in the manner and for the purpose set forth.

JOHN HARVEY.
FREDERICK HERKSTROETER.
